METHOD OF TEACHING THE DEAF TO HEAR AND MUTES TO SPEAK

Filed Oct. 11, 1926

Patented July 10, 1928.

1,676,716

UNITED STATES PATENT OFFICE.

HAROLD L. WARWICK, OF FORT WORTH, TEXAS.

METHOD OF TEACHING THE DEAF TO HEAR AND MUTES TO SPEAK.

Application filed October 11, 1926. Serial No. 140,959.

My invention relates to amplifying sound-
ing devices for teaching the deaf to hear and
for teaching mutes to speak; and the object
is to produce simple devices for first detect-
ing whether or not a patient has a residuum
8 of hearing that would come within the voice
range and then provide means for enabling
the deaf or hard of hearing to hear music,
musical sounds, or the human voice, and to
10 hear their own voices, and in this manner
teach them to speak. The process is to drill
the patients in the preliminary stages until
they can learn and appreciate sounds both
in hearing and speaking. Other objects and
15 advantages will be fully explained in the
following description and the invention will
be more particularly pointed out in the
claims.

Reference is had to the accompanying
20 drawings which form a part of this application.

Fig. 1 is a perspective view of the appa-
ratus or machine.

Fig. 2 is a plan view of the machine with
25 the top removed to show the complete work-
ing devices.

Fig. 3 is a side elevation of a receiver jack.

Fig. 4 is a diagrammatic view of the
“hook-up.”

30 Similar characters of reference are used
to indicate the same parts throughout the
several views.

The apparatus is provided with two trans-
mitter jacks 1 and 2. The jack 1 is elec-
35 trically connected to the primary 3 and the
jack 2 is electrically connected to the pri-
mary 4. There are two primaries on the
transmitting side of one secondary. The
primaries 3 and 4 consist of two coils which
40 are electrically connected to the common
point 5. The point 5 is electrically con-
nected to the rheostat 6 by a wire 7, and
through the rheostat 6 to the negative A
battery. The secondary 8 is connected to
45 the in-put terminals 9 and 10 of an ordinary
three-stage resistance coupled amplifier, us-
ing vacuum tubes 11 and having plates 12
and grids 13, in connection with the pos-
itive and negative of B batteries. The ma-
50 chine is provided with two out-puts 14 and
15 for connection with the ear 'phones. The
receiver jack 15 is connected directly with
the positive pole of the B battery and also
electrically connected to the three-stage am-
plifier by connections through plates 12.

55 The receiver jack 14 is connected to the

positive pole of the same B battery and also
connected with the jack 15 and with the am-
plifier plates 12. The receiver jacks 14 and
15 are also connected to the filament control
60 rheostat 16. A feature of this invention is
that there are two primaries on the trans-
mission side of the coils and only one sec-
ondary on the opposite side of the core 17.
Two parallel wires are wound on the core 65
which constitutes the primary of the trans-
mitters 1 and 2. The out-put of the second-
ary is impressed on the grid 13 of the first
amplifying tube 11 and this is repeated
70 through all the tubes 11 of the amplifier in
the ordinary manner. A plug in the re-
ceiver jack 15 will light up all tubes 11 of
the amplifier and a plug in the receiver 14
will light up only one tube 11, the tube next
75 to the secondary 8.

To start with a new pupil, the circuits are
connected with a musical instrument of some
kind,—a phonograph or similar instrument,
and the pupil puts on the ear 'phones.
There may be several pupils,—each having
80 a pair of ear 'phones. They will usually
show by the expression of the face when
they hear. The teacher uses one trans-
mitter to teach the pupils while the pupils wear
the ear 'phones. A pupil is also required to
85 make sounds or talk through a transmitter
held in his hands at the same time he wears
the ear 'phones. In this way he hears his
own voice and thereby learns to modify his
speech, in his efforts to imitate his teacher.
90 Two jacks 14 and 15 are used as the out-put.
15 is an added stage to further increase the
amplification of the sound. The amplifica-
tion mechanism includes audio resistance
amplification 18 and fixed condensers 19.
95

The pupil in order to hear his own voice
may use either jack 1 or jack 2 and use ear
'phones connected to either jack 14 or jack
15. The teacher can determine by experi-
100 ment which receiving jack the pupil should
use. The teacher can use either jack 1 or
jack 2.

What I claim, is,—

1. The method of training the voice of
persons of defective hearing and speech, 105
which consists in electrically transmitting to
such person through bone construction am-
plified speech sounds, causing the person
to simulate the sounds which he hears, and
transmitting and amplifying the same simi-
larly to the original sounds to his own hear-
ing senses for comparison.
110

2. The method of training the voices of persons of defective hearing and speech, which consists in electrically transmitting to such person sounds for detecting whether or 5 not a person has a residuum of hearing, commencing with low sounds and gradually amplifying the sounds until the hearing is detected, causing the person to simulate the sounds which he hears, and transmitting and 10 amplifying the same similarly to the original sounds to his own hearing senses for comparison.

3. The method of training the voices of persons of defective hearing and speech, which consists in electrically transmitting to such person amplified speech sounds, causing the person to simulate the sounds which he hears, transmitting and amplifying the same similarly to the original sounds to his own hearing senses for comparison, 15 and causing the person to hear his own voice. 20

In testimony whereof, I set my hand, this 14th day of September, 1926.

HAROLD L. WARWICK.
